UNITED STATES PATENT OFFICE.

JOHN H. McLEOD, OF TOPEKA, KANSAS.

ROAD-MACHINE.

1,337,241.

Specification of Letters Patent. Patented Apr. 20, 1920.

Application filed May 22, 1919. Serial No. 298,983.

To all whom it may concern:

Be it known that I, JOHN H. McLEOD, a citizen of the United States, and a resident of Topeka, in the county of Shawnee and State of Kansas, have invented certain new and useful Improvements in Road-Machines, of which the following is a specification.

My invention is an improvement in road machines, and has for its object to provide a machine of the character specified which will work the road whether wet or dry, crushing lumps when dry and squeezing the water out of the ruts and packing the soil from the high places to the low places when wet, and afterward finishing and smoothing the road, wherein the crushing and packing is brought about by a roller having a spiral or spiral ribs which works the soil as it moves thereover.

20 In the drawings:

Figure 1 is a side view of the improved machine;

Fig. 2 is a longitudinal section;

Fig. 3 is a plan view;

25 Fig. 4 is an enlarged detail showing one of the tension rollers for the driving chain;

Fig. 5 is a section on the line 5—5 of Fig. 2;

Fig. 6 is a detail of the scraper operating 30 mechanism;

Fig. 7 is a vertical section through one of the bearings of the finishing roller;

Fig. 8 is a front view of the packing roller, with the frame in section;

35 Fig. 9 is a similar view of another form of packing roller.

In the present embodiment of the invention a suitable frame 1 is provided, which is supported at its rear end by a finishing roller 2 and at its front end by a pair of front wheels 3. These wheels 3 are journaled on spindles 4 on the ends of an axle 5, which is yieldingly connected with the frame, and the spindles are hinged to the ends of the 45 axle, and are connected to move together by means of a link 6 which is pivoted at its ends to arms 7 extending rearwardly from the spindles.

A plate 8 is secured to the top of the axle, 50 and it will be noticed that this axle is of hollow construction, being square in the present instance, and the ends of the plate 8 are offset upwardly, as indicated at 9.

Each of the said ends is slidably connected by a rod 10 with the frame 1, and a coil spring 11 is arranged between the frame and each of the upwardly offset ends 9, the spring acting normally to press the frame upwardly. The rod 10 being, however, slidably connected with the offset end 9 of the 60 plate may move downwardly with respect thereto, thus providing a spring support for the frame.

The roller 2 has journal pins 12 at its ends, and these pins are journaled in sectional 65 bearings on the under sides of plates 13. Each of these plates has an upwardly curved portion 14 at its rear end, which is pivoted to the frame 1 as indicated at 15 at the rear end of the frame. At their forward ends 70 the plates 13 have openings through which extend pins 16 depending from the frame 1, and a coil spring 17 encircles each pin between the plate 13 and the frame, acting normally to press the plate downward. Thus a 75 yielding mounting is provided for the roller 2. This roller is driven to propel the machine, by means of the sprocket chains 18. Each of these chains connects sprocket wheels 19 and 20 on the journal pin 12 and 80 on a transmission shaft 21 which is journaled transversely of the frame below the same and which is adapted to be connected with a suitable motor arranged upon the frame, as, for instance, an internal combustion engine, in any usual or well known manner.

The shaft 21 is journaled in bracket plates 22 depending from the frame and the upper run of each chain 18 is tensioned by an idler 90 23 which is arranged on a brace plate 24 extending longitudinally of the frame. The machine is steered by means of a steering column 24 which is suitably supported by the frame, the said column having at its 95 lower end a worm 25 which meshes with a worm wheel 26 journaled on an auxiliary frame 27 which connects the front axle with a cross bar 28 of the frame. This wheel 26 is connected by a link 29 with the arms 7 of 100 one of the spindles, and it will be obvious that when the wheel 26 is rotated by means of the steering column the wheels 3 will be swung to guide the frame.

The packing roller 30 is arranged in front 105 of the finishing roller, the said packing

- roller having a shaft 31 whose ends are journaled in the rear ends of the plates 32 whose forward ends are pivoted to the frame 1, as indicated at 33. Rods 34 are connected 5 with the ends of the shaft 31, each of the rods having an eye engaging the shaft, and these rods extend upwardly through the frame 1 and are engaged by wheeled nuts 35 above the frame. Thus by means of the 10 wheeled nuts the shaft 31 may be raised or lowered to raise or lower the packing roller with respect to the frame, that is, to regulate the pressure of the packing roller on the soil.
- 15 The roller 30 may have a single spiral rib 36 as shown in Fig. 8, the said rib being continuous from one end to the other, or the roller 37, as shown in Fig. 9, may have a spiral rib 38 at each end, the said ribs being 20 symmetrical and acting to force the soil outwardly in both directions from the center of the roller. Either form of roller may be used, the rollers being interchangeable. Guide brackets 39 depend from the frame 1 25 adjacent to each plate 32, to guide the vertical movement of the said plates during adjustment.

As shown in Fig. 7, the journal pins 12 are journaled in sectional bearings 40 on the 30 plates 13, the sections of the bearings being secured to each other and to the plates by bolts and nuts 41. The journal pins are arranged within a bushing 42 and a ball bearing 43 is arranged within the bushing between the shaft and the bushing.

The upper section of the bearing and the plate have registering openings forming an oil passage, and an oil cup 44 is connected with the opening for lubricating the bearing. It will be noticed, referring to Fig. 7, 40 that the bushing has an opening registering with those of the plate and the upper bearing section.

Means is provided for scraping accumulations of soil off the peripheral surface of the finishing roller. The said means comprises a scraper blade 45 which is secured to a shaft 46 journaled in the frame 1 in rear of the roller 2. Rods 47 are connected with 45 the opposite ends of the scraper blade, and these rods pass forwardly and upwardly at an incline through bearing plates 48 on the frame. Wheel nuts 49 engage the rods above the bearing plate, and it will be evident that by turning the wheel nuts in the proper direction the scraper blade may be moved toward or from the finishing roller to scrape accumulations therefrom.

In operation, either type of packing roller 60 may be used, namely, that shown in Fig. 8 or that shown in Fig. 9. The machine is self-propelled and is guided by means of the wheel on the steering post 24. The packing roller 30 moving over the road surface 65 packs the soil or road material, moving

it from the high places and filling up the low places. If the soil is muddy it is worked just the same, the water being squeezed out and permitted to drain away. Afterward, the finishing roller 2 comes into play, thoroughly smoothing and packing the soil or road material to present a finished surface. 70

The finishing roller is provided with a hood 50 which covers the top of the same, the hood being secured to the main frame. 75

I claim:

1. A machine of the character specified comprising a main frame, front wheels for supporting the front end of the frame and arranged to swing to guide the frame, a 80 finishing roller journaled transversely of the frame at the rear thereof, means for driving said roller to propel the frame, and a packing roller journaled transversely of the frame in front of the finishing roller 85 and vertically adjustable, said packing roller having a spiral rib on the periphery thereof for the purpose specified, plates pivoted to the opposite sides of the frame near the front thereof, the said roller being journaled in the rear ends of the plates, and means connected with the said rear ends for raising and lowering the same. 90

2. A machine of the character specified comprising a main frame, front wheels for 95 supporting the front end of the frame and arranged to swing to guide the frame, a finishing roller journaled transversely of the frame at the rear thereof, means for driving said roller to propel the frame, and 100 a packing roller journaled transversely of the frame in front of the finishing roller and vertically adjustable, independently of the finishing roller.

3. A machine of the character specified 105 comprising a main frame, front wheels for supporting the front end of the frame and arranged to swing to guide the frame, a finishing roller journaled transversely of the frame at the rear thereof, means for 110 driving said roller to propel the frame, a packing roller journaled transversely of the frame in front of the finishing roller and vertically adjustable, plates pivoted to the frame at the rear corners thereof and extending forwardly below the frame, the finishing roller having journal pins journaled on the said plates, and springs arranged between the forward ends of the plates and the frame. 115

4. A machine of the character specified comprising a main frame, a packing roller arranged transversely of the frame intermediate its front and rear ends, an auxiliary frame pivoted at its front end to the main 125 frame and carrying at its rear end the packing roller, and a connection between the main frame and the rear end of the auxiliary frame for adjusting said rear end of the auxiliary frame vertically, wheels for sup- 130

porting the front end of the main frame, and a finishing roller for supporting the rear end of the main frame.

5. A machine of the character specified comprising a main frame, a packing roller arranged transversely of the frame intermediate its rear and front ends, an auxiliary frame pivoted at its front end to the main frame and carrying at its rear end the pack-

ing roller, and a connection between the main frame and the rear end of the auxiliary frame for adjusting said rear end of the auxiliary frame vertically.
